POUCH

Harry H. Hunter, Arlington, Mass.

Application August 17, 1934, Serial No. 740,222

6 Claims. (Cl. 206—41)

This invention relates to improvements in pouches, particularly pouches for tobacco, and more particularly pouches for the transportation, storage, vending and use of material such as 5 tobacco. The invention also comprises a method of manufacture of such improved pouches.

It is one of the objects of the present invention to provide a moisture-proof package of pouch form for material such as tobacco, which 10 shall be compact, easily accessible and highly durable, and which shall be so relatively inexpensive that the cost of the material contained in it is not substantially affected by the cost of the packaging and the package may be thrown away 15 when the material has been used.

Another object of the invention is to provide an inexpensive moisture-proof pouch-type package adapted to maintain its original form of a pouch throughout all the normal conditions of 20 transportation, sale and use and which shall afford the buyer or user a substantially full view 25 of its contents at all times.

Another object is to so relate the useful adjunct of a conventional pipe cleaner with a package of smoking tobacco that the cleaner serves 25 to stiffen the package and assists in perfecting a complete seal of the same against loss of the moisture content of the tobacco, and by means 30 of which the package may be quickly and conveniently given its initial opening after purchase.

It is a further object of the invention to employ method steps and materials by which a package having some or all of the above characteristics may be quickly and inexpensively produced 35 without necessitating special or costly equipment.

Other objects will be either apparent or particularly pointed out hereinafter.

While the invention in certain of its aspects 40 may involve the use of only a single layer or ply of "Cellophane" or similar material, the present embodiment, shown in detail in the accompanying drawings, is chiefly centered around the idea of a double ply body from which the pouch 45 pocket is formed, as by this method of construction many of the important advantages of the package are obtained. If, for example, the double ply body is formed by doubling a single strip of the body material upon itself, the fold 50 so made may be presented as a strong rigid edge for the pocket of the pouch, susceptible to perfect sealing and capable of withstanding all normal conditions of usage. Other folds of the package are maintained more uniform than would be 55 the condition with a single ply body, and the

uniformity of these folds is helpful in obtaining and maintaining a moisture-sealing package particularly desirable in connection with smoking tobacco to prevent loss of flavor or aroma which otherwise escapes with the moisture vapor. 5

The doubled strip of body material also lends itself readily to the method of edge binding contemplated by the invention, and a pouch body having a pocket portion and extended long wrapper portion is easily and inexpensively 10 formed.

Principal aims, therefore, of the invention are to provide an attractive sealed package of smoking tobacco for vending, which may be easily 15 opened and thereafter carried in the user's pocket as a pouch, and to provide a package of high quality tobacco which shall be proof against the admission of dust, oil, air and moisture, and likewise proof against the escape of moisture, even after it has been opened and is being used 20 from time to time; thereby preserving the usefulness of the tobacco over a long period.

The accompanying drawings show a preferred embodiment of the invention and one of various other possible embodiments thereof; also, the 25 steps of the method employed in making up the package.

Fig. 1 is a side edge view of a single strip of thin, flexible, transparent body material folded upon itself. 30

Fig. 2 is a top plan view of the folded strip shown in Fig. 1.

Fig. 3 is a side edge view of the body material again folded upon itself for a portion of its length to form a pocket portion with extended wrapper 35 portion.

Fig. 4 is a plan view of the body as shown folded in Fig. 3, but with the addition of marginal binding tape to secure the folds and bind the 40 edges.

Fig. 5 is a somewhat enlarged sectional view taken on the line 5—5 of Fig. 4.

Fig. 6 is a somewhat enlarged sectional view taken on the line 6—6 of Fig. 4.

Fig. 7 is a somewhat enlarged sectional view taken on the line 7—7 of Fig. 4. 45

Figs. 8, 9, 10 and 11 are schematic views indicating the extent to which the pocket is filled with tobacco and the general manner of folding the pocket portion and the wrapper. In these schematic views, for the sake of clearness the multiple ply construction has been disregarded. 50

Figs. 12, 13 and 14 are views indicating a preferred manner of making the original seal of the 55

package by the use of a pipe cleaner and a revenue stamp or other sealing strip.

Figs. 15 and 16 illustrate another form of seal for the package, Fig. 15 showing the reverse side or back of the package as customarily arranged for vending and Fig. 16 showing the front of the package.

Fig. 17 is an enlarged cross-sectional view of the package shown in Figs. 12 to 14, the section being taken on the line 17—17 of Fig. 14.

Fig. 18 is an enlarged cross-sectional view of the package shown in Figs. 15 and 16, the section being taken on the line 18—18 of Fig. 16.

Referring now more in detail to the drawings, 15 a single strip of thin, flexible, tough, transparent and moisture-resistant material is shown in Fig. 1 at 20 doubled back upon itself lengthwise and creased in a definite transverse line producing an edge 21. The double ply body so formed is then 20 doubled upon itself for a fraction of its length, as shown in Fig. 3, forming a pocket portion 22 and an extending wrapper portion 23. By this fold what eventually serves as the bottom edge 24 of the pocket is of two plies of the thin material, and 25 the edge which serves as the top of the pocket is the hard folded edge 21 produced by the first doubling operation.

With the piece as folded in Fig. 3, marginal binding tape is applied, first the side tapes or 30 strips 25 along the side edges from one end of the folded body to the other, and then the end strips 26 and 27 which are caused to overlap the side strips at the corners as shown at 28 in Fig. 4. This marginal binding tape is preferably 35 highly adhesive on one side and may be any of a number of moisture-resistant tapes used for sealing or binding. The side strips 25 embrace the two double ply margins of the pocket portion 22 as shown in Figs. 4 and 7, thus effectually sealing 40 the pocket at each side, and also embrace the side margins of the wrapper portion 23, thereby joining the two ply wrapper at each side. The end strip 26 closes the two ply wrapper at its flap end, and the end strip 27 defines and reinforces 45 the lower edge of the pocket portion and maintains the ends of the side strips in pocket sealing position.

It will be obvious from the foregoing that a pouch pocket is formed and that a long two ply wrapper extends from one side of the pocket (see Figs. 4 and 8).

Smoking tobacco or other material is then deposited in the pocket in a predetermined quantity less than sufficient to completely fill the pocket 55 (Fig. 8) and the pouch body is then again folded in a transverse line substantially at the point 30. In making this fold the upper portions of the pocket walls are pressed closely together and turned back over the partly filled pocket together 60 with the wrapper portion as shown clearly in the schematic view Fig. 9. The actual top edge 21 of the pocket, considering the pouch as it is when filling it or using it to fill a pipe, is thus turned back over the outwardly bulging wall 31 of the 65 pocket and pressed against this wall by drawing the wrapper. In this condition a new top edge 32 of the pocket is provided by the fold 30 which presents a doubled two ply margin 33 against the wall 34 of the pocket at the region of the fold 70 30. This provides a very effective seal at what in this condition of the package is the top of the pocket; but to further insure sealing, the long wrapper of the package is brought to bear against the reverse fold 35 of the pocket wall and the 75 actual top edge 21 of the pocket in its position

opposite the bellied portion of the package as indicated at 36 in Figs. 9 and 18, and from there the wrapper is continued tightly around the package and drawn tightly against the taped bottom edge 24 (Fig. 10) and the prior pocket fold 30 at what may in this condition be considered the top of the package (Fig. 11). The wrapper flap 38 extends well down over the pocket after it has passed the fold 30, the wrapper thus passing at least completely around the folded pocket containing the filler material.

The thin transparent body is preferably of non-fibrous material such as moisture-proof "Cellophane", but it is of course within the scope of the invention that some other material be used 15 having similar or substantially like characteristics. The word "transparent" as used herein is not intended to exclude a material which is translucent or other material which permits the contents of the package to be viewed through 20 the material.

The description thus far is intended as an illustration of the general manner of forming and wrapping the package irrespective of the particular method of originally sealing the same for 25 shipment, storage and vending purposes. It serves also to illustrate the condition of the package in the hands of the user after the original seal has been broken and the package is being used from time to time to withdraw material. It will 30 be obvious from the foregoing that the package, when in the hands of user with the original seal broken, still retains to a high degree its moisture-resistant characteristic at the option of the user, and may be carried in his pocket for a long 35 period of time and the contents completely used without the package breaking down or in any way losing its pouch form.

The original sealing of the package may be carried out in various ways, two of which are illustrated in the drawings. A preferred form of original sealing is shown in Figs. 12, 13, 14 and 17. In this form a conventional pipe cleaner 50 having a soft-coated bendable wire has one or both ends bent out of line as indicated at 51 and the remaining straight body portion 52 laid along the top of the pocket wall near and substantially parallel to the top edge 21, as shown in Fig. 12. A sealing strip 53 which is preferably a gummed revenue stamp of standard form required for 50 tobacco packages is then moistened and applied over the body portion of the pipe cleaner and on both sides thereof along its unbent length. As shown in Fig. 13, the stamp attaches to the upper margin of the pocket wall and to the inner 55 side of the wrapper and seals the opening of the pocket. This is done before the pocket is folded and subsequently the pocket and wrapper are folded as described in connection with Figs. 8, 9, 10 and 11. The straight wire portion assists 60 in producing and maintaining an effective seal, preventing any tendency of the pocket edge to pleat in the sealing or buckle in packing or transportation, and the wire also provides longitudinal reinforcement of the package. One or the other 65 of the bent ends 51 left uncovered by the sealing strip serves as a means to take hold of the wire and use it to quickly and conveniently mutilate the stamp and simultaneously open the pocket. The cleaner is of a length with its ends 70 bent that it may then be deposited lengthwise in the pouch, if desired, handy for use when needed.

With this form of original seal it is not usual to employ any tie strip or binder for the wrapper. 75

- It has been found that the flap portion of the wrapper if carried sufficiently toward the lower end of the package will conform substantially to the shape of the package and rest in proper position. Optionally, of course, a light rubber band 5 may be applied around the package or a small sticker seal may be used to bind the flap end of the wrapper to the package, thus preventing the possibility of the flap becoming disarranged.
- Another form of original sealing is shown in Figs. 15, 16 and 18. In this form the sealing strip is not applied over the top edge 21 of the pocket and the package is more dependent at all times upon the seals effected by the folds of the 10 pocket at 30 and the seals effected by the surrounding wrapper at the various regions heretofore mentioned, than is the other package wherein such seals are of most importance after the package is in use. As shown clearly in Figs. 15 15 and 18, after the package body has been folded across the top of the pocket and tightly and completely wrapped, the sealing strip 60, preferably a revenue stamp as in the other form, is applied longitudinally of the package to the wrapper near 20 its flap end, and the ends 61 of the stamp are carried around the ends of the folded pouch and affixed to the wrapper on the other side as shown 25 in Figs. 16 and 18.
- The label and notice respectively shown at 30 30 and 71 in the drawings may conveniently be applied as stickers on the transparent strip in such relation and location that when the strip is folded they are protected between the layers or plies of the body or between the pocket and the 35 wrapper and are unexposed to the contents of the package or to the action of anything exteriorly thereof, yet they will be visible through the transparent material of the body. It is preferred, however, to print these on the "Cellophane" as their 40 final position may be readily determined inasmuch as the quantity of tobacco in each package is the same and the positions of folds and wrappings are substantially uniform.
- Automatic machinery may be used to carry out 45 all of the steps of the method outlined above, but the method is adapted to the rapid and inexpensive production of such packages by hand labor. The package is suited to convenience in shipping, display and vending, and may be carried 50 by the purchaser in his pocket as a shapely, compact pouch adapted to retain the flavor and aroma of the tobacco and without liability of escape of any of the tobacco into his pocket or the admission of foreign matter to the pouch pocket.
- It is obvious that should a single thickness of 55 "Cellophane" or similar material be used as a body instead of the double ply strip described, the reinforcement afforded by the pipe cleaner and the assistance of it in effecting a perfect seal of the top of the pocket and in providing a ready means 60 of opening the pocket would be of even more importance than in the preferred forms shown in the drawings. In these forms the folds of the double plies so average the natural irregularities 65 in the thin material that sufficiently straight and rigid edges are produced. With a single ply body, reinforcement of some kind is essential and this is conveniently afforded by the combined cleaner-and-stamp seal.
- What is claimed is:
1. A tobacco pouch package having a transparent body in which a portion of the transparent body material is doubled back upon itself 70 to form a pocket portion with an extending wrapper portion, binding tape over the side edges 75 of the doubled-back body closing the sides of the pocket, tobacco in the pocket of less amount than would fill the pocket, that portion of said pocket beyond the tobacco being folded back upon itself and the extending wrapper being carried around the pocket, and means for closing said pocket against original access and adapted to assist in preventing the escape of moisture, comprising a pipe cleaner laid over the top margin of the pocket and a sealing strip affixed to said margin and overlying the pipe cleaner and affixed to a portion of the extending wrapper. 5
2. A tobacco pouch package having a transparent body in which a portion of the transparent body material is doubled back upon itself 10 to form a pocket portion with an extending wrapper portion, binding tape over the side edges of the doubled-back body closing the sides of the pocket, tobacco in the pocket of less amount than would fill the pocket, that portion of said pocket 15 beyond the tobacco being folded back upon itself and the extending wrapper being carried around the pocket, and means for closing said pocket against original access and adapted to assist in preventing the escape of moisture, comprising a pipe cleaner laid over the top margin of the pocket and a sealing strip affixed to said margin and overlying the pipe cleaner and a portion of the extending wrapper, said pipe cleaner 20 having a bent end not entirely covered by said sealing strip. 25
3. A tobacco pouch package having a transparent body in which a portion of the transparent body material is doubled back upon itself 30 to form a pocket portion with an extending wrapper portion, binding tape over the side edges of the doubled-back body closing the sides of the pocket, tobacco in the pocket of less amount than would fill the pocket, that portion of said pocket beyond the tobacco being folded back upon itself 35 and the extending wrapper being carried around the pocket, and means for closing said pocket against original access and adapted to assist in preventing the escape of moisture, comprising a pipe cleaner laid over the top margin of the pocket and a sealing strip affixed to said margin and overlying the pipe cleaner and a portion of the extending wrapper, said pipe cleaner 40 having a bent end not entirely covered by said sealing strip. 45
4. A smoker's package comprising a strip of transparent moisture-resistant material such as 50 "Cellophane" doubled upon itself to provide a transverse hard-folded edge and doubled again for a portion of its length to provide a pocket portion, of which said hard-folded edge defines the top of the pocket, and an extending wrapper 55 portion, means closing the sides of said pocket and the side and top edges of said wrapper portion, a quantity of tobacco in said pocket less than enough to fill the same, a pipe cleaner on the pocket adjacent said hard-folded edge and a binding strip over said pipe cleaner and secured to the pocket on one side thereof and to the extending wrapper portion on the other side thereof to close said pocket. 60
5. A smoker's package comprising a body of transparent moisture-resistant material such as 65 "Cellophane", formed with a pocket and a long wrapper extending from a wall of the pocket, tobacco in said pocket insufficient to fill the same, 70 and means for closing the walls of the pocket together at the top beyond the tobacco, comprising a pipe cleaner positioned along the top margin of the pocket and a sealing strip overlying the cleaner and secured on opposite side 75

of the same to the margin of the pocket and the adjacent wrapper portion respectively.

6. A smoker's package comprising a body of transparent moisture-resistant material such as 5 "Cellophane", formed with a pocket and a long wrapper extending from a wall of the pocket, tobacco in said pocket insufficient to fill the same, and means for closing the walls of the pocket together at the top beyond the tobacco, compris-

ing a pipe cleaner positioned along the top margin of the pocket and a sealing strip overlying the cleaner and secured on opposite side of the same to the margin of the pocket and the adjacent wrapper portion respectively, said cleaner having an offset end portion protruding from the sealing strip. 5
